UNITED STATES PATENT OFFICE.

HORACE S. FAIRBANKS, OF RACINE, WISCONSIN.

CARRIAGE SEAT AND BODY.

SPECIFICATION forming part of Letters Patent No. 398,597, dated February 26, 1889.

Application filed November 19, 1888. Serial No. 291,266. (No model.)

To all whom it may concern:

Be it known that I, HORACE S. FAIRBANKS, a citizen of the United States, residing at Racine, in the county of Racine and State of 5 Wisconsin, have invented certain new and useful Improvements in Carriage Seats and Bodies, of which the following is a specification.

This invention relates to the corners of all 10 rectangular receptacles, such as boxes, traveling-trunks, wagon-bodies, carriage-bodies, and all kinds of seats for same. In fact, it is applicable to most anything requiring a strong and at the same time a neat or tasty 15 corner, the object being to avoid the use of glue or nails, or both, and to provide a corner which will not be easily marred or nicked, of great strength, and not affected by the atmosphere; and the invention consists of the 20 novel construction and combination of the parts described and claimed in the following specification, and clearly illustrated in the accompanying drawings, forming an inseparable part thereof, of which—

25 Figure 1 is a broken perspective view of a carriage-body having my improvements applied. Fig. 2 is a sectional plan of one corner as when its sides are vertical and put together in accordance with my improvements.

30 Fig. 3 shows the same parts partially separated. Fig. 4 is a section taken through the corner of a seat made in accordance with my improvements. Fig. 5 is a broken plan view of same, and Fig. 6 a simple modification.

35 Similar reference-letters designate like parts throughout the various views.

A is the body portion, and B the seat portion, of a light carriage-body to which my 40 improvements are applied. When the corner to be made is to form a perfect right angle, the ends of the panels C C are cut or sawed off on an angle of about forty-five degrees in a manner to leave their inner sides the long- 45 est—*i. e.*, just the reverse of the way they would be sawed were they to be mitered together—and connected by means of an inside and outside metallic plate, these being drawn and secured firmly together by either ma- 50 chine screws or rivets or bolts, the inside

plate, D, being provided with tongues *d* upon those sides which come in contact with the wooden panels C C, and in the latter are formed grooves *c c* at the proper point to receive said tongues *d d*. The opposite side of 55 the said plate D is preferably concaved, as shown. An outside plate, E, has one side flat and the other, as viewed in cross-section or at its ends, formed either curvilinear on the segment of a circle or of three flat sur- 60 faces, as seen by dotted lines in Fig. 5. The flat side *e* of this plate E is placed so as to come in contact with the beveled ends of the panels C C and the flat center portion of the plate D, and machine-screws may pass loosely 65 through either plate and be threaded to the other, by which they may be secured together, or ordinary rivets, F, may be used for the purpose; also, bolts may be used.

The tongues *d d* are preferably thinner or 70 slightly sharp on their edges, and the grooves *c c* of the panels C C made correspondingly. The plate E may also have angular tongues or small projections *e' e'*, fitting grooves *c' c'* in the said panels C C, if desired, as seen in 75 Fig. 2; but by providing the plate E with suitable beads, *e² e²*, on its edges and making the joint as seen in Fig. 3 an ornamental finish is obtained which, when painted and var- 80 nished, has a very pleasing effect.

If desired, a half-round wooden or metallic bead, G, may be secured at the top, so as to completely cover and conceal the ends of the metallic plates D E, as shown.

It is obvious that a series of short prongs 85 projecting from the plate D in a manner to embed themselves in the sides C C would be a substantial equivalent for the tongues *d d*.

Having described my improvements, what I claim as new, and desire to secure by Letters Patent, is—

1. The combination, with the panels having their ends beveled and sides grooved, substantially as shown, of the metallic plates D E, and means for securing said panels 95 between said plates, in connection with bolts or rivets for clamping said plates firmly together.

2. The combination of the panels having their ends beveled and provided on their in- 100

ner sides with vertical grooves, as shown, an angle-plate having vertical tongues fitting the vertical grooves in said panels, an outside vertical plate bearing against the beveled ends of said panels and the said angle-plate, and bolts or rivets clamping said plates and the panels securely together.

In testimony whereof I affix my signature in presence of two witnesses.

HORACE S. FAIRBANKS.
